ROTARY POWER LAWN MOWER

Finn T. Irgens, Wauwatosa, Wis., assignor to Outboard Marine Corporation, Waukegan, Ill., a corporation of Delaware

Filed July 22, 1957, Ser. No. 47,047

Term of patent 14 years

(Cl. D40—1)

FIG. 1 is a front perspective view of a rotary power lawn mower embodying my new design.

FIG. 2 is a rear perspective view thereof showing the side opposite that shown in FIG. 1.

FIG. 3 is a vertical cross-sectional view thereof taken on line 3-3 of FIG. 2.

FIG. 4 is a perspective view of the housing member of the rotary power lawn mower shown in FIGS. 1, 2 and 3.

FIG. 5 is a reduced scale perspective view of said housing member taken diagonally opposite the view shown in FIG. 4.

FIG. 6 is a vertical cross-sectional view taken on line 6-6 of FIG. 4.

FIG. 7 is a bottom perspective view of the housing member.

The important feature of the design is the shape of the housing.

I claim:

The ornamental design for a rotary power lawn mower, as shown and described.
